BY *Mark Roth*
MS. ATTORNEY

UNITED STATES PATENT OFFICE.

ORANGE O. OZIAS, OF DAYTON, OHIO.

DESIGN FOR A SCALE BASE-PLATE.

SPECIFICATION forming part of Design No. 28,946, dated June 28, 1898.

Application filed June 6, 1898. Serial No. 682,788. Term of patent 14 years.

all whom it may concern:

Be it known that I, ORANGE O. OZIAS, of Dayton, county of Montgomery, and State of Ohio, have invented a certain new and useful design for a Scale Base-Plate, of which the following is a description, reference being had to the accompanying drawings, forming a part hereof, in which like figures refer to like parts.

In the drawings, Figure 1 is a plan view of scale base-plate formed in accordance with my design. Fig. 2 is a sectional elevation thereof on line $\alpha\alpha$ of Fig. 1, and Fig. 3 is a reduced plan view of the surface of said plate opposite that shown in Fig. 1, these three figures being deemed necessary to fully illustrate my design.

The leading or material feature of my design consists of a rectangular plate having a circular ring and a bordering-flange project-

ing, respectively, from the surface and edges of one face of said plate.

In the drawings, 10 illustrates the rectangular plate, 11 the circular ring projecting from the surface of said plate, and 12 illustrates the bordering-flange projecting from the edges of said plate. The ring 11 and flange 12 project from the same surface of said plate 10, and the flange 12 projects farther than said ring 11. 30

What I claim is—

The design for a scale base-plate, substantially as shown and described.

In witness whereof I have hereunto set my hand this 14th day of March, 1898.

ORANGE O. OZIAS.
